UNITED STATES PATENT OFFICE.

GEORGE A. PINGREE AND RICHARD A. UHLIN, OF SEATTLE, WASHINGTON.

OIL-BURNER-AIR-SUPPLY REGULATOR.

1,210,981.

Specification of Letters Patent.

Patented Jan. 2, 1917.

Application filed September 26, 1916. Serial No. 122,262.

To all whom it may concern:

Be it known that we, GEORGE A. PINGREE and RICHARD A. UHLIN, both citizens of the United States, residing at Seattle, in the county of King and State of Washington, have invented certain new and useful Improvements in Oil-Burner-Air-Supply Regulators, of which the following is a specification.

10 This invention relates to oil burners of the wickless class which, by their own heat, vaporize the oil then introduce air and burn the gaseous mixture. To produce complete combustion and the consequent intense heat 15 the conditions to be considered are, the mixture of oil-vapor and air in due proportions, either at the sea level, on mountain tops, or at any intermediate height, and under the varying conditions of different 20 styles of burners and the different service they perform.

The object of our invention is to adapt an air supply regulator to meet these various requirements.

25 To this end, our invention consists in the construction and combination of parts hereinafter more fully described, and particularly stated in the claims, reference being had to the accompanying drawings in 30 which;

Figure 1 represents in side elevation, partly in longitudinal, vertical section an oil burner air supply regulator with the gage-rod in service, according to our invention. Fig. 2 represents the air intake tube 35 and the air gate in position for service.

Numeral 1 represents the oil vapor supply pipe leading into jet 2, the delivery nozzle 3, of which—shown in Fig. 2 as discharging a spray of vapor—is in central line of the gate tube 11, which communicates through a passage 4, with the usual mixing chamber a portion of the bottom of which is shown at 5. The jet 2 with its 40 base cap 6 its side cap 7 and its lever 8 for operating a cleaning device is not peculiar to this invention. The intake tube 9 is open at both ends and removably engages the jet 2 in a neat cylindrical fit at 10. The gate tube 45 11 is screw-threaded into the upper side of the intake tube 9, and fits movably into the passage 4 in order that it may be rotated to screw to and from the nozzle 3, thus decreasing or increasing the size of the opening 50 for the free passage of air into it. A

gage rod 12 in tapering or wedge-like form, with indices 13 marked at intervals upon it, is adapted to be inserted as shown in Fig. 1, between the ends of the gate 11 and the nozzle 3 to locate the adjustment of the gate, 55 then it is to be removed leaving free passage—as shown in Fig. 2—for the jet of vapor from the nozzle 3 to be forced under pressure into the tube 11, drawing in with it air in such quantity as the opening 60 at the end of the gate will permit. The gage-bar may have two, four, or more sides marked with scales adapted to units of different styles of measurement. The marking shown on the gage in the drawing may 65 indicate feet above sea level, and the gage set as shown would be suitable to admit the required amount of air at an altitude of 70 3750 feet when a nozzle is used having a delivery outlet .016 of an inch in diameter, as 75 indicated on this side of the gage near its end. Burners for some purposes require a larger nozzle opening, the diameter of which would be marked on the same side of the gage as the corresponding scale numerals. 80 For such purposes the gage rod may have any suitable number of sides to receive the required markings to indicate the proper set of the air gate 11.

In all the varying conditions the position 85 of the graduating marks must be located upon the gage by actual experiment at a considerable expense of time and labor, but when once established, any number of gage rods may therefrom be graduated, so that a 90 burner to meet the requirements of any customer may be quickly set to produce the best results, and if the customer be provided with a gage he can easily readjust his burner if he should move to a different altitude or 95 if conditions affecting the air intake were otherwise changed. If each purchaser of an oil burner equipped with this device be instructed in this simple mechanical means of properly adjusting it he will find it to work 100 with more economy and generally with better results than burners not so equipped.

We claim:

1. In an oil burner air supply regulator, the combination with an air and oil-vapor 105 mixing chamber having a passage through its bottom and a delivery nozzle for oil-vapor located to deliver into the said aperture, of an intake tube open at both ends and fitted upon the said nozzle for free removal, 110

and a gate tube fitting the said passage to rotate and to slide longitudinally and screwthreaded into one side of the intake tube.

- 5 2. An oil burner air supply regulator comprising an air intake tube open at both ends and adapted at one side to receive an oil-vapor delivery nozzle; and a gate tube screwthreaded into the other side opposite
- 10 to the said nozzle and fitted through the bot-

tom of the air and oil mixing chamber for rotary and longitudinal movement therein.

In testimony whereof we affix our signatures in presence of two witnesses.

GEORGE A. PINGRÉE.
RICHARD A. UHLIN.
